UNITED STATES PATENT OFFICE.

MAX B. SCHARLES, OF NEW YORK, N. Y., ASSIGNOR TO SCHARLES BROTHERS.

DESIGN FOR A FRAME FOR TOY SAND-MILLS.

SPECIFICATION forming part of Design No. 26,325, dated November 24, 1896.

Application filed July 16, 1896. Serial No. 599,445. Term of patent 3½ years.

To all whom it may concern:

Be it known that I, MAX B. SCHARLES, a citizen of the United States, residing at New York, in the county of New York and State 5 of New York, have invented and produced a new and original Design for Toy Sand-Mill Frames, of which the following is a full, clear, and exact specification.

My design relates to toys, and particularly 10 to that class of toys known as "sand-mills," wherein sand falling from a hopper upon a paddle-wheel causes the latter to revolve.

The object is to produce a design for a frame for such a sand-mill as will be simple and contain but few elements, but which at the same 15 time will present the appearance of being in fact a complicated structure.

The design will be more particularly described with reference to the accompanying 20 drawings, in which the figures represent a perspective view of a sand-mill frame embodying my invention.

Figure 1 is a front view in perspective, and Fig. 2 a side view of the same.

The leading features of my design are the 25 vertical standards *a a*, substantially parallel to each other, the raised base *b*, the base *c*, having scalloped edges *c'*, the braces *d d*, and hopper *e*, the latter being rectangular in shape and also having scalloped edges *e'*.

f is a paddle-wheel on post *a*.

Having thus described and illustrated my invention, I claim—

The design for a frame for toy sand-mills, herein described and illustrated.

In testimony whereof I affix my signature in presence of two witnesses.

MAX B. SCHARLES.
